UNITED STATES PATENT OFFICE.

BERT O. TILDEN, OF NEW YORK, N. Y., ASSIGNOR TO AMERICAN SANITARY WORKS,
OF NEW YORK, N. Y., A CORPORATION OF NEW JERSEY.

DESIGN FOR A FLUSH-TANK.

40,402.

Specification for Design. **Patented Dec. 14, 1909.**

Application filed May 11, 1909. Serial No. 495,370. Term of patent 14 years.

To all whom it may concern:

Be it known that I, BERT O. TILDEN, a citizen of the United States, residing at New York, in the county of New York and State of New York, have invented a new, original, and ornamental Design for a Flush-Tank, of which the following is a specification, reference being had to the accompanying drawing, forming part thereof.

The figure is a perspective view of a flush-tank, showing my new design.

I claim:

The ornamental design for a flush-tank, as shown.

BERT O. TILDEN.
